LOOM ELEMENT.

1,361,530.

Specification of Letters Patent.

Patented Dec. 7, 1920.

Application filed September 9, 1916. Serial No. 119,210.

To all whom it may concern:

Be it known that I, HOWARD I. MORRIS, a citizen of the United States, residing at San Diego, in the county of San Diego and State 5 of California, have invented new and useful Improvements in Loom Elements, of which the following is a specification.

This invention relates to loom elements, and more particularly to certain elements of 10 that loom construction and organization disclosed in another application for U. S. Letters Patent for looms, filed by me September 9, 1916, Serial Number 119,208. In said identified application the various loom elements 15 of the present invention are described, disclosed, and claimed in association with other features of the complete loom construction and organization. In the present application claims are to be directed at the 20 loom elements separately or in combination, or such thereof as are intimately and immediately associated and combined and inter-related, and more particularly with relation to what is designated or described in 25 said other identified application as the weft-producing means, or means for associating with the partially-formed fabric the weft units or elements. In said other identified application a particular object of the invention 30 is set forth as being the provision of a loom constructed and organized with the capability of producing a bias-woven fabric, or fabric in which the warp and weft thread units are related, warp to weft, at an angularity of approximately 90 degrees, but more 35 particularly are related each to the side edge or edges of the fabric at angles of less than 90 degrees; and said invention of said identified application further contemplates the 40 provision of selvage portions or units at the side edges of the bias-woven fabric, and preferably independent of the warp and weft unit threads, and serving, as long as associated with the warp and weft units, to prevent 45 distortion or lengthwise stretch of the fabric. The present invention is not to be understood as limited to any particular complete organization or construction of a loom, or any loom devised for the purpose of turning 50 out any particular or specific pattern or weave or organization of fabric, whether bias-woven, provided with a selvage unit or units, or of whatever other design or structural entity. The present invention relates 55 to loom elements for providing and asso-

ciating weft units with the warp units of a fabric, irrespective of the specific design of the fabric or the inter-relation of the warp and weft units or their relation to the fabric side edges, and irrespective of the finish or 60 structure of the side edge portions of the fabric. The invention, in addition to these different considerations and factors, has as its objects the provision of novel and improved loom elements which will be superior in point of relative simplicity and 65 inexpensiveness in construction and organization taken in connection with durability and freedom from liability of breakage or dis-organization, positiveness in operation, 70 facility in control, and necessitating a minimum of requirement of care and attention, and of great adaptability to varying conditions and environments of use and service, and which will be generally superior in 75 efficiency and serviceability.

With the above and other objects in view, the invention consists in the novel and useful provision, formation, construction, combination, association and inter-relation of parts, 80 members and features, all as hereinafter described, shown in the drawings and finally pointed out in claims:

In the drawings:

Figure 1 is an end elevation of a group or 85 assemblage of loom elements organized and adapted for producing weft-fabric units and associating the same with warp-fabric units to be suitably supplied;

Fig. 2 is a top plan view of the same, parts 90 being broken away;

Fig. 3 is a detail fragmentary transverse sectional view of the same, taken upon the line x^3-x^3 , Fig. 1, and looking in the direction of the appended arrows, other features 95 likewise being thrown into section;

Fig. 4 is an enlarged fragmentary top plan view, and partially broken away and sectioned detail view, of a shuttle-needle constituting one of the loom elements shown in 100 Figs. 1 and 2;

Fig. 5 is a side edge view of the shuttle-needle shown in Fig. 4;

Fig. 6 is a detail fragmentary sectional view of a portion of the shuttle-needle, showing associated therewith temporary retaining means to which the weft thread is applied in producing the weft thread units; 105

Fig. 7 is a detail fragmentary view, partly in section, and similar to part of the showing 110

in Fig. 4, of the shuttle-needle and a plurality of the temporary retaining means such as shown in Fig. 6, such as utilized at the respective ends of a given weft thread unit, 5 the showing in Fig. 6 being with respect to the temporary retaining means as employed at one end of a given weft thread unit;

Fig. 8 is a view similar to Fig. 6 showing a modified form of the shuttle-needle and a 10 modified organization of the temporary retaining means, such modified form being utilized in the use of a plurality of weft threads for producing weft thread units of multiple organization;

15 Fig. 9 is a view similar to Fig. 7 showing said modified form of the shuttle-needle and plural retaining means for the use of a plurality of weft threads in the production of multiple weft thread units; and

20 Fig. 10 is a detail fragmentary side elevation of a portion of the showing in Figs. 8 and 9, upon a slightly reduced scale with respect to the scale of said other figures;

25 Figs. 5, 6, 7, 8 and 9 are likewise all upon an enlarged scale.

Corresponding parts in all the figures are designated by the same reference characters.

Referring with particularity to the drawings, the improved and novel loom elements 30 disclosed therein comprise, in the main, a shuttle-needle A by which the weft thread or threads *a* is or are thrown or applied so as to be resultantly associated with the warp thread units or the partially-completed fabric (not shown); weft thread supply means B from which such weft thread or weft threads is or are furnished to the shuttle-needle A; weft thread guide means *b* which may be included within the weft 35 thread supply means B, and whereby the weft thread furnished to the shuttle-needle is definitely determined or controlled as to amount or length for each stroke of the shuttle-needle; temporary retaining means 40 C whereby the weft thread or threads is or are held during the formation of a given single or multiple weft thread unit, and for such time thereafter as may be desired in accordance with the provision and operation 45 of all the elements of a given loom including such retaining means; operating means D for the shuttle-needle A; and operating means E for the temporary retaining means C. Associated with the 50 other mentioned elements is a table F over which the fabric which has received the weft thread units is passed to such further means for taking off or disposing of the fabric or operating upon it as may be provided in any particular construction and organization 55 of loom. This table is shown as having a surface portion *f* over which the work is passed, which is curved transversely, or arcuate, to conform to the path of the shuttle-needle A, which is likewise shown as curved 60

or arcuate and playing in a segmental path. The temporary retaining means C are disposed adjacent to one end 11 of the table F, namely, the end next adjacent to the path of play of the shuttle-needle A. The operating means E for the temporary retaining means C preferably include a rotatable shaft 12, from which the table F may be supported as by a plurality of spider arms 13 which radiate from a web 14 carried upon a hub 75 15 loosely surrounding the shaft 12. Such web 14 is provided with radial guides or keepers 15^a utilized in the mounting and accommodation of the operating means E for the temporary retaining means C. The 80 shuttle-needle A is carried at the outer end of a radial arm 16 provided at its inner end with a hub 17 fast upon a tubular shaft 18 loosely surrounding the concentric shaft 12, and suitably controlled and actuated by 85 means (not shown) to impart to said radial arm 16 oscillatory movement to cause the shuttle-needle A to execute insertion and withdrawal strokes, whereby the weft thread *a* is shot into the suitably supplied partially- 90 completed fabric to introduce therein and associate therewith the weft thread units.

In Fig. 1 the shuttle-needle A and its carrying arm 16 are shown in full lines in the positions assumed at the end of the insertion 95 stroke, and in dotted lines in the positions assumed at the end of the withdrawal stroke.

The tubular shaft 18 revolves upon the concentric shaft 12 by means of a bushing 100 19 within the tubular shaft and fast thereto; and the shaft 12 revolves within a journal 20 which is supported at the upper end of a standard or pedestal 21. Two properly organized cams 22 and 23 are fixed upon the 105 shaft 12, and operate respectively upon cam rollers 24 and 25 provided at the inner ends of radial rods 26 and 27 respectively, which latter with such rollers and cams are included within the operating means E for the 110 temporary retaining means C. The rods 27 play through the guides or keepers 15^a above mentioned. The radial arm 16 is provided at its outer end with a suitable block 28 through an opening in which the shuttle-needle body 29 is passed, a set screw or the like 30 being mounted in the block to hold the shuttle-needle in position. The shuttle-needle body is curved, in the construction shown in the drawings, to conform to a true 115 arc, and its rearward or inner end, inward of the block 28, is bent laterally as at 29^a and upwardly and laterally deflected as at 29^b to terminate in an open mouth or thread guide 29^c, such body 29 being tubular 120 throughout its entire length with the exception of its outer or forward or leading end portion 29^d, which is solid and tapered or rounded to a point so as to more effectively 125 pass through the shed of the warp threads 130

on the insertion stroke. Adjacent to the point or leading end 29^a, the tubular shuttle-needle body 29 is provided with a lateral eye or opening 29^e, which communicates with the interior of the body 29, but only at one side, not being a through opening. As shown in Figs. 8, 9 and 10, a plurality of such eyes or openings 29^e may be provided at the forward end of the shuttle-needle body, for accommodation of a plurality of weft threads *a*, and the application thereof to the partially-completed fabric in the employment of the temporary retaining means C in plural provision. The weft thread *a* is furnished to the needle A, as stated by supply means B, which serve to tensionally supply such weft thread, the same comprising a standard 31 rising from a suitable weft thread ball support 32 carrying a weft thread ball or balls 33, provided in number in accordance with whether a single or more weft thread *a* is or are to be supplied; a rocker arm 34 being mounted to oscillate at the upper end of such standard 31, as at 35, intermediate of its ends, one end thereof being urged downwardly by a contractile coil spring 34^a connected therewith, and the other end thereof being connected with an adjustable bracket 35^a surrounding the standard 31. A transverse arm 36 is connected with the standard 31 immediately below the rocker arm 34, which latter is provided at its end opposite that engaged by the spring 34^a, with a thread guide or eye 37, such transverse arm 36 likewise being provided at its outer end with a thread guide 38 for the ball 33 from which thread is to be supplied, or with one such guide for each such bobbin, and from which the thread or threads leads or lead to the thread guide or eye 37 at the end of the rocker arm 34. From such eye 37 the thread is led to and enters the thread guide 29^e at the inner deflected end of the shuttle-needle body, whence the thread is led through the tubular shuttle-needle body and outwardly through the eye or eyes 29^e to be introduced within the partially-completed fabric and associated temporarily with the temporary retaining means C.

The weft thread guide means *b* included generally within the weft thread supply means B comprises a curved or segmental or arcuate guide plate 38 mounted upon the base 39 of the standard 21, and ranging in an arc slightly greater than and substantially co-extensive with the arc of the path of travel of the shuttle-needle body 29, and at one side of the same, and having at one side a radial flange 38^a, namely, at the edge remote from the path of travel of the shuttle-needle body 29. The arrangement of the several features is such that the weft thread guide means *b* is disposed first in order, counting toward the table F, the path

of the shuttle-needle body 29 is next in order, the retaining means C are next in order, and the table F is next in order. It results in the operation of the shuttle-needle and the supply means B and weft thread 70 guide means *b*, that the thread or threads *a* is or are directly fed over the curved guide 38, upon the withdrawal stroke of the shuttle-needle A, and more thread is laid upon said guide than is required to supply the 75 shuttle-needle in the insertion stroke of the shuttle-needle; so that upon the insertion stroke the rocker arm 34, depressed at the end carrying the eye 37 during the withdrawal stroke of the needle, may rise gradually under the action of the spring 34^a, and put the thread *a* being fed to the shuttle-needle under yielding tension, so as to prevent any distortion of the needle body 29 or prevent any loosening or overlapping 80 or entangling of the thread fed from the eye or eyes 29^e of the shuttle-needle. Of course upon the withdrawal stroke of the shuttle-needle likewise sufficient thread is supplied to and through the shuttle-needle 90 for constituting the respective one-half of the weft thread unit introduced within the partially-completed fabric upon such withdrawal stroke of the shuttle-needle. Of course the thread introduced on each stroke 95 may, if desired, be considered a weft thread unit in itself.

The temporary retaining means C further comprise retaining pins 40, one disposed adjacent to each end of the path of play of the leading end 29^a of the shuttle-needle A, unless there be a plurality of weft threads *a* to be introduced within the partially-woven fabric to produce a multiple weft thread unit, as indicated in Figs. 8, 9 and 10, 100 in which case there are an equal plurality of such retaining pins 40 so provided in each instance, in either case such retaining pin or retaining pins being mounted at the outer end of a rocker arm 41 fulcrumed as at 42 105 beneath the table F, so that such retaining pins may be swung radially of the table and projected beyond the outer surface or periphery *f* thereof, by the rods 26 and 27 respectively, of the operating means E of 110 such temporary retaining means. Each rocking arm is pivotally connected as at 42^a to the rod 26 or 27, and is jointed outwardly of the respective fulcrum 42, as at 41^a, which fulcrum is between the ends of 115 the rocking arm, to provide an extreme outer end portion 41^a which carries the pin or pins 40; and as clearly shown in Fig. 3 such subdivided or jointed end of each rocker arm 41 is capable of adjustment as 120 between its parts by means of an adjusting screw 41^b threaded through a projecting portion of one such subdivision of the rocker arm and bearing upon a projecting portion 125 of the other subdivision thereof, thus deter- 130

mining the extent to which the respective retaining pin or pins 40 may be projected beyond the periphery of the table F. Likewise, bearing upon a pin 41^c upon the inner side of each such arm extremity 41^a is a leaf spring 41^d, the inner end of which is connected with the other end of the rocking arm 41, as at 41^e, permitting the extremity 41^a to swing at the joint 41^f, so that the pin or pins may be directly radially withdrawn from the loops at the ends of the weft thread units, at the proper time, without exerting undue strain upon the same or catching upon or breaking the thread or otherwise becoming unduly engaged with the fabric.

The weft thread supply means B may be caused to exert a more effective tension upon the weft thread or threads *a* by providing, as shown, guide pins 38^a upon the transverse arm 36, and providing a further thread guide 38^b at the fulcrum 35 of the rocker arm 34, the respective weft thread *a* being looped about such pins 38^a and passed 25 through the thread guide 38^b before being passed through the thread guide 37.

The operation, method of use and advantages of the several loom elements in the combination and inter-relation thereof, 30 namely, the loom elements hereinabove described and disclosed in the drawings will be readily understood from the foregoing description taken in connection with said accompanying drawings and the following statement:—

The weft thread or threads *a* is or are continuously supplied to the thread guide or open mouth 29^c of the deflected end portion 29^b of the tubular body 29 of the shuttle-needle A. The said shuttle-needle is given its throw or its insertion and withdrawal strokes in reciprocation, by suitably imparted oscillations of the tubular shaft 18, and before each insertion stroke the operating means E of the temporary retaining means C are put into operation, by a suitable turning of the shaft 12, which operates the cam 22 to so throw the rod 27 as to project the retaining pin or pins 40 at the right-hand portion of the assembled elements in Figs. 1, 2 and 3, to so project the same that the weft thread or threads *a* is or are engaged with the same to form a loop in the thread or threads, as shown in Figs. 55 6, 7, 8 and 9 at the left-hand side of said figures, the shuttle-needle then pursuing its curved path, emitting thread or threads *a* from its eye or eyes 29^e as it travels. Substantially at the moment when the needle 60 leading end arrives at the outer end of its insertion stroke, the operating means E of the temporary retaining means C act through the shaft 12 and the cam 23 of the rod 26 to project the pin or pins 49 at the left-hand side of Figs. 1 and 2, and at

the right-hand side of Figs. 7 and 8, so that the thread or threads *a* is or are caught by said pin or pins, thus forming another loop or other loops in the thread or threads to conserve which loop or loops said pin or pins act during the withdrawal stroke of the shuttle-needle. Thus the two lengths of thread or threads necessary to form a weft thread unit or course are impaled upon the pins 40 at the two opposite loops surrounding said pins, and may be thus held until such means (not shown) as may be employed are utilized to compact the newly formed weft thread unit or finally dispose it compactly with the other portions of the 80 fabric to pass over the periphery *f*, of the table F. Thereupon, or at such time as predetermined, the operating means E are caused to act by a further turning of the shaft 12 to cause the cams 22 and 23 to cause 85 the rods 26 and 27 to play outwardly and rock the rocker arms 41 and readily withdraw the retaining pins 40 or multiples of such pins, accompanied by a yield of the rocker arms 41 at the joints 41^f, under opposition of the leaf springs 41^d, thus effecting easy withdrawal of such retaining pins from the loops in the weft thread unit formed, leaving said unit or the newly completed single or multiple unit, in position 95 in association with the other portions of the fabric. As stated, the degree to which the retaining pins may be projected by inward movement of the rollers 24 and 25 over the cams 22 and 23 is determined by the 100 manipulation and position of the adjusting screws 41^b. As the shuttle-needle A travels upon its withdrawal stroke, in addition to the thread required to be introduced by that stroke in the fabric, more than sufficient thread is laid upon the guide 38 of the guide means *b* to supply the shuttle-needle in its succeeding insertion stroke, so that, as above stated, the feed of thread to the shuttle-needle upon such insertion stroke 110 is effected under tension of the spring-affected rocker arm 34, which, having been lowered at its end carrying the eye 37 during the withdrawal stroke of the shuttle-needle, now rises at said end, asserting a tension or pull upon the thread and controlling uniformly the strain upon the leading end 29^d of the needle and keeping the thread from catching or tangling, and preventing 115 supplying of thread.

The thread readily feeds laterally from the needle through the eye or eyes 29^e, as successive weft thread units are produced and added to the organization of the fabric. While means for supplying the warp thread 125 units are not shown in the drawings or described herein, nor means for producing the proper shape of formation of said warp thread units to receive the weft thread units introduced by the shuttle-needle A, it will 130

- be understood that such features are to be provided in the complete loom within which the loom elements of the present invention are incorporated, such provisions being 5 made in the complete loom organization disclosed and described in said other application for U. S. Letters Patent hereinabove identified. The inner end portion of 29^b of the shuttle-needle body 29 is deflected outwardly and laterally as described so that the thread guide 29^c may overlie the curved 10 guide 38. The flange 38^a acts to prevent displacement of the thread from the guide 38.
- 15 It is manifest that many changes and modifications and variations may be made in adapting the invention to various conditions of use and service, and which departure may be made from the specific provision, construction, combination, association and inter-relation of parts, members 20 and features herein shown and described:— all without departing from the spirit of the invention and a fair interpretation thereof.
- 25 Having thus disclosed my invention, I claim and desire to secure by Letters Patent:
1. In weft producing means for looms, the combination with means for introducing weft thread units to a partially completed 30 fabric, retaining pins for temporarily engaging the weft thread units, jointed arms carrying the pins and having a yielding action at the joints thereof, and means for actuating the arms.
  - 35 2. In weft producing means for looms, the combination with means for introducing weft thread units to a partially completed fabric, of pins temporarily engaging the weft threads, yieldably mounted members carrying the pins, and means for actuating the yieldably mounted members to move the pins into and out of operative position.
  - 45 3. In weft producing means for looms, the combination with a rock shaft, a curved needle carried by the rock shaft and having the axis of the shaft as its center of curvature, said needle moving in a curved path as the shaft is rocked, a concentric shaft, 50 and means actuated by the concentric shaft for temporarily retaining the weft threads in position.
  - 55 4. In weft producing means for looms, the combination with a rock shaft, of a curved needle carried by the rock shaft and having the axis of the shaft as its center of curvature, said needle moving in a curved path when the shaft is rocked, a tubular shaft concentric with the rock shaft, and 60 means actuated by the tubular shaft for temporarily retaining the weft threads in position.
  - 65 5. In weft producing means for looms, the combination with a rock shaft, of a curved tubular needle carried by the rock shaft and
- having the axis of the shaft as its center of curvature, said needle moving in a curved path as the shaft is rocked and being provided at one end thereof with an open mouth for the entrance of the weft thread 70 and at the other end thereof with an eye for the exit of the weft thread, and means for temporarily retaining the weft thread units in position.
6. In weft producing means for looms, 75 the combination with a rock shaft, a tubular curved needle carried by the rock shaft and having the axis of the needle as its center of curvature, said needle moving in a curved path as the shaft is rocked and being provided at one end with an open mouth through which the weft thread enters the needle, and at the other end with an eye through which the weft thread leaves the needle, a second shaft concentric with the 80 rock shaft, and means actuated by the second shaft for temporarily retaining the weft thread units in position.
7. In weft producing means for looms, 85 means for introducing weft thread courses to the partially completed fabric, and means for supplying weft thread thereto; said last named means comprising a tensional feed device in connection with which the thread is supplied, and weft thread guide means 90 over which thread is so supplied; said first named means being mounted to operate in a path adjacent to said weft thread guide means whereby more thread is supplied than is required in one phase of operation of said 95 first named means.
8. In weft producing means for looms, 100 means for introducing weft thread courses to the partially completed fabric, and means for supplying weft thread thereto; said last named means comprising a tensional feed device in connection with which the thread is supplied, and weft thread guide means over which thread is so supplied; said first 105 named means being mounted to operate in a path adjacent to said weft thread guide means whereby more thread is supplied than is required in one phase of operation of said first named means; said first named means comprising a reciprocating element.
9. In weft producing means for looms, 110 means for introducing weft thread courses to the partially completed fabric, and means for supplying weft thread thereto; said last named means comprising a tensional feed device in connection with which the thread is supplied, and weft thread guide means over which thread is so supplied; said first 115 named means being mounted to operate in a path adjacent to said weft thread guide means whereby more thread is supplied than is required in one phase of operation of said first named means; said first named means comprising a reciprocating element.
- 120 10. In weft producing means for looms, means for introducing weft thread courses to the partially completed fabric, and means for supplying weft thread thereto; said last named means comprising a tensional feed device in connection with which the thread is supplied, and weft thread guide means over which thread is so supplied; said first named means being mounted to operate in a path adjacent to said weft thread guide 125 means whereby more thread is supplied than is required in one phase of operation of said first named means; said first named means comprising a reciprocating element adapted to travel in a curved path, and said 130

- weft thread guide means comprising a curved guide the arc of curvature of which is of greater radius than the curved path of said reciprocating element.
- 5 10. In weft producing means for looms, means for introducing weft thread units to the partially completed fabric, and means for tensionally supplying weft thread thereto; said last named means comprising a 10 rocker arm, said rocker arm having a thread guide disposed to oscillate in the oscillation of said rocker arm and through which thread is passed to said first named means, and means exerting a tendency to oscillate 15 said rocker arm; in combination with a weft thread guide means in connection with which weft thread is fed to such first named means in excess of the amount required for one phase of operation of said first named 20 means.
11. In weft producing means for looms, means for introducing weft thread units to partially completed fabric, and means for temporarily retaining said weft thread units 25 so introduced; said last named means comprising a retaining pin, and means for projecting said retaining pin into position of service and withdrawing it therefrom; said last named means comprising a rocker arm, 30 and means for oscillating said rocker arm; said retaining pin being mounted upon said rocker arm, and said rocker arm being jointed at the portion thereof carrying said retaining pin and being provided with means 35 for relatively adjusting the jointed parts to vary the degree of projection of said retaining pin.
12. In weft producing means for looms, means for introducing weft thread units to 40 partially completed fabric, and means for temporarily retaining said weft thread units so introduced; said last named means comprising a retaining pin, and means for projecting said retaining pin into position of 45 service and withdrawing it therefrom; said last named means comprising a rocker arm, means for oscillating said rocker arm, said retaining pin being mounted upon said rocker arm, said rocker arm being jointed at 50 the portion thereof carrying said retaining pin, and means being provided as between said jointed portions to permit said retaining pin to yield upon withdrawal from position of service.
- 55 13. In weft producing means for looms, means for introducing weft thread units to the partially completed fabric, and means for temporarily retaining said weft thread units so introduced; said last named means 60 comprising a rocker arm, a retaining pin mounted upon the rocker arm, a rod pivotally connected with the rocker arm, a roller carried by the rod, and a cam coöperating

with the roller to produce through the rod and roller oscillation of the rocker arm. 65

14. In weft producing means for looms, means for introducing weft thread units to the partially completed fabric, means for temporarily retaining said weft thread units so introduced, and means for operating each 70 of said foregoing means, including concentric revoluble shafts one of which is tubular.

15. In weft producing means for looms, means for introducing weft thread units to the partially completed fabric, and an extended 75 guide for the weft thread disposed adjacent to the path of operation of the first named means; said first named means being adapted to operate in a curved path, and said guide being curved and disposed parallel to the curved path of said first named means.

16. In weft producing means for looms, means for introducing weft thread units to the partially completed fabric, and an extended 85 guide for the weft thread disposed adjacent to the path of operation of the first named means; said first named means being adapted to operate in a curved path, and said guide being curved and disposed parallel 90 to the curved path of said first named means; said first named means comprising a reciprocating element provided with a projecting portion which executes a path of movement closely adjacent to said guide. 95

17. In a loom, means for supplying weft thread, the same including a tension device comprising a rocker arm, means exerting a tension upon said rocker arm, a thread guide at one end of said rocker arm, and a thread 100 supply from which thread is led to said thread guide; there being a further thread guide at the center of oscillation of said rocker arm and through which thread is fed to said first named thread guide. 105

18. In a loom, the combination with a tubular shuttle-needle having an eye through which weft thread is introduced to partially completed fabric, means for supplying to the tubular shuttle-needle a greater amount 110 of weft thread upon the withdrawal stroke of the shuttle-needle than is required in the insertion stroke of the shuttle-needle, and a tensional thread supply for the shuttle-needle comprising a rocker arm, means tensionally acting upon the rocker arm, and thread guides at the center of oscillation of the rocker arm and at one end thereof through which thread is supplied. 115

In testimony whereof, I have signed my 120 name to this specification in the presence of two subscribing witnesses.

HOWARD I. MORRIS.
